CLAIM

The ornamental design for a drain cover, as shown and described.

DESCRIPTION

FIG. 1 is a perspective view of a drain cover showing the design;

FIG. 2 is a top plan view of the drain cover of FIG. 1; FIG. 3 is a bottom plan view of the drain cover of FIG. 1; FIG. 4 is a front elevational view of the drain cover of FIG. 1;

FIG. 5 is a rear elevational view of the drain cover of FIG. 1;

FIG. 6 is a left elevational view of the drain cover of FIG. 1;

FIG. 7 is a right elevational view of the drain cover of FIG. 1; and,

FIG. 8 is an enlarged right elevational view of the drain cover of FIG. 1 with a vertical break line for ease of reference.

The dash-dash broken lines in the drawings depict portions of the drain cover that form no part of the claimed design. The dot-dash-dot broken lines in the drawings define the boundaries of the claim and form no part thereof. FIG. 8 is shown with a symbolic break in its length. The appearance of any portion of the drain cover between the break lines forms no part of the claim.
